US00D944040S

(12) United States Design Patent (10) Patent No.: US D944,040 S
(45) Date of Patent: * Feb. 22, 2022

(54) STORAGE FURNITURE

(71) Applicant: Julius Blum GmbH, Hochst (AT)
(72) Inventor: Andreas Holzapfel, Bregenz (AT)
(73) Assignee: JULIUS BLUM GMBH, Hoechst (AT)
() Term: 15 Years

(21) Appl. No.: 35/509,342

(22) Filed: Nov. 11, 2019

(80) Hague Agreement Data

Int. Filing Date: Nov. 11, 2019
Int. Reg. No.: DM/205993
Int. Reg. Date: Nov. 11, 2019
Int. Reg. Pub. Date: May 15, 2020

(30) Foreign Application Priority Data

May 16, 2019 (EM) 006473583
(51) LOC (13) Cl. 06-04
(52) U.S. Cl. ..... USPC D6/657
